LADY'S STOCKING

Melvin J. Gordon, Brookline, Mass.

Application January 3, 1950, Serial No. 6,975

Term of patent 14 years

(Cl. D47—7)

To all whom it may concern:

Be it known that I, Melvin J. Gordon, a citizen of the United States, residing at Brookline, State of Massachusetts, have invented a new, original, and ornamental Design for a Lady's Stocking, of which the following is a specification, reference being had to the accompanying drawing, forming a part hereof, in which the figure shows a perspective side view of a lady's stocking embodying my new design.

I claim:

The ornamental design for a lady's stocking, as shown.

MELVIN J. GORDON.
